UNITED STATES PATENT OFFICE.

ARTHUR E. WIEDENHOEFT, OF CHICAGO, ILLINOIS.

DESIGN FOR A BRIDGE LAMP.

Application filed April 27, 1923. Serial No. 5,969. Term of patent 3½ years.

To all whom it may concern:

Be it known that I, ARTHUR E. WIEDENHOEFT, a citizen of the United States, residing at Chicago, in the county of Cook and State of Illinois, have invented a new, original, and ornamental Design for a Bridge Lamp, of which the following is a specification, reference being had to the accompanying drawing, forming part thereof.

The figure is a perspective view of a bridge lamp showing my new design.

I claim:

The ornamental design for a bridge lamp, as shown.

ARTHUR E. WIEDENHOEFT.
